US0D1004814S

(12) **United States Design Patent** (10) **Patent No.:** **US D1,004,814 S**
(45) **Date of Patent:** **** Nov. 14, 2023**

(54) **OUTDOOR SPEAKER LAMP**

- (71) Applicant: **SAVANT TECHNOLOGIES LLC**,
Cleveland, OH (US)
- (72) Inventors: **Ming Lei**, Shanghai (CN); **Huisheng Zhou**, Shanghai (CN); **Yin Suo**, Shanghai (CN); **Jean Chen**, Shanghai (CN)
- (73) Assignee: **SAVANT TECHNOLOGIES LLC**,
East Cleveland, OH (US)
- (**) Term: **15 Years**
- (21) Appl. No.: **29/846,434**
- (22) Filed: **Jul. 15, 2022**

Related U.S. Application Data

- (63) Continuation-in-part of application No. 29/720,615, filed on Jan. 14, 2020, now abandoned.

(57) **CLAIM**

The ornamental design for an outdoor speaker lamp, as shown and described.

DESCRIPTION

FIG. 1 is a top view of the outdoor speaker lamp; FIG. 2 is a front elevational view thereof; FIG. 3 is a right side elevational view thereof; FIG. 4 is a back elevational view thereof; FIG. 5 is a bottom view thereof; and, FIG. 6 is a perspective view of the outdoor speaker lamp of FIG. 1 shown in an alternate configuration of use. In the drawings, the broken lines depict portions of the outdoor speaker lamp that form no part of the claimed design.

1 Claim, 6 Drawing Sheets
